(57) **CLAIM**

The ornamental design for an integrated water container for cleaning robot, as shown and described.

DESCRIPTION

1. Integrated water container for cleaning robot
2. Integrated water container for cleaning robot

1.1 : Front

1.2 : Back

1.3 : Left

1.4 : Right

1.5 : Top

1.6 : Bottom

1.7 : Perspective

1.8 : Perspective

1.9 : Perspective

2.1 : Front

2.2 : Back

2.3 : Left

2.4 : Right

2.5 : Top

2.6 : Bottom

2.7 : Perspective

2.8 : Perspective

2.9 : Perspective

(Continued)

1.1 is a front view of a first integrated water container for cleaning robot; 1.2 is a back view thereof; 1.3 is a left view thereof; 1.4 is a right view thereof; 1.5 is a top view thereof; 1.6 is a bottom view thereof; 1.7 to 1.9 are three perspective views thereof. 2.1 is a front view of a second integrated water container for cleaning robot; 2.2 is a back view thereof; 2.3 is a left view thereof; 2.4 is a right view thereof; 2.5 is a top view thereof; 2.6 is a bottom view thereof; 2.7 to 2.9 are three perspective views thereof.
